Primary Examiner — Marianne N Pandozzi(74) *Attorney, Agent, or Firm* — Scherrer Patent & Trademark Law, P.C.; Stephen T. Scherrer; Monique A. Morneau(57) **CLAIM**

The ornamental design for a beverage conditioning and dispensing apparatus, as shown and described.

DESCRIPTION

FIG. 1 is a perspective top view of a water dispenser; FIG. 2 is a front side thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawing depict environmental subject matter only and form no part of the claimed design.
